UNITED STATES PATENT OFFICE.

GEORGE E. WILLIAMS AND AURA M. WILLIAMS, OF BARTLETT, KANSAS,
ASSIGNORS OF ONE-THIRD TO ARTHUR F. BUVINGER, OF BARTLETT,
KANSAS.

FOOT-POWER HAMMER.

No. 799,285.

Specification of Letters Patent.

Patented Sept. 12, 1905.

Application filed July 9, 1904. Serial No. 215,939.

To all whom it may concern:

Be it known that we, GEORGE E. WILLIAMS and AURA M. WILLIAMS, citizens of the United States, residing at Bartlett, in the county of Labette, State of Kansas, have invented certain new and useful Improvements in Foot-Power Hammers; and we do hereby declare the following to be a full, clear, and exact description of the invention, such as will enable others skilled in the art to which it appertains to make and use the same.

This invention relates to foot-power hammers; and it has for its object to provide a construction wherein the blow of the hammer may be accomplished by the pressure of a foot-lever and in which the hammer may be swung laterally to strike upon different portions of the face of an anvil.

A further object of the invention is to provide a construction which will permit of vertical adjustment of the hammer to suit different conditions of operation and in which, furthermore, the head of the hammer may be adjusted so that its face may be in proper relation to the work when the blow is struck.

Other objects and advantages of the invention will be understood from the following description.

In the drawings forming a portion of this specification, and in which like numerals of reference indicate similar parts in the several views, Figure 1 is a side elevation of the hammer, the near side of the upright frame being broken away. Fig. 2 is a rear elevation of the apparatus. Fig. 3 is an elevation of a front or the portion adjacent to the anvil. Fig. 4 is a top plan view. Fig. 5 is a vertical section through the machine in the common plane of the mast and the hammer-handle. Fig. 6 is a horizontal section through the mast just above the lower clutch. Fig. 7 is a horizontal section through the hammer-head and a part of the handle thereof.

Referring now to the drawings, the present apparatus comprises a base-frame including sills 10 and 11, at the ends of which are the cross-pieces 12 and 13, and within the enclosure of one end of this frame is secured the block 14, upon which is mounted the anvil 15, which latter extends transversely of the frame.

Upon the sills 10 and 11 are mounted the arches 16 and 17, against the outer side faces of which are secured the bifurcated lower

ends of the sides 18 and 19 of an arched frame, the top 20 of which is flat. The arches 16 and 17 are connected by the cross-piece 21, in which is rotatably mounted a mast 22, which engages rotatably a perforation 23 in the top 20 of the arch-frame. The mast is continued above the arched frame, and upon its upper end is mounted a yoke-plate 24, the free ends of which are bent outwardly in opposite directions and have mounted thereon the pillow-blocks 25 and 26, in which is journaled a rock-shaft 27. The yoke-plate is held upon the upper end of the mast by means of the nut 25', engaged with the reduced upper end of the shaft and holding the yoke-plate upon the shoulder at the base of its reduced portion of the mast. The rock-shaft carries a transverse seat 28, in which is disposed the handle 29 of a hammer, the handle being held in the seat by means of clips 30, which when loosened permit of adjustment of the handle longitudinally of the seat, so that the head of the hammer may be in proper position in relation to the face of the anvil.

The rock-shaft is held normally and yieldably with the hammer-head raised from the anvil by means of a helical spring 31, which is attached at one end to a crank-arm 32 at one end of the rock-shaft, while its opposite end is connected to a turnbuckle 33, which is connected in turn to an arm 34, which projects from the side of the mast.

Upon the sills 10 and 11 are mounted pillow-blocks 35 and 36, in which is disposed a rock-shaft 37, on which is fixed a block 38, having the spaced ears 39, between which is pivoted the downwardly-turned end of a treadle 40, the opposite end of which operates in a guide 41, secured to the side of the anvil base or block.

The shaft 27 carries a peripherally-grooved segment 41, at one end of which groove is attached a chain 42, which lies in the groove and passes from the opposite end thereof adjacent to the anvil downwardly between the anvil and the arched frame, where it is connected to a turnbuckle 43, which is also connected with the treadle. When the treadle is depressed, the chain is pulled downwardly, so that the segment is rotated and the shaft 27 is rocked to swing the hammer-head down upon the face of the anvil. When the treadle is released, the helical spring moves the rock-

shaft 27 in the opposite direction, so that the hammer is raised from the anvil.

- By reason of the rotary movement permitted the mast, the hammer may be swung with its head laterally to strike different parts of the anvil, the mast being shifted rotatably by means of the handle 44, one end of which is pivoted between the ears of a clip 45, secured to the mast above the arched frame.
- 10 The mast is also slidably vertically in its bearings to raise and lower the hammer, and to hold the mast at different points of its vertical adjustment a collar 48 is mounted upon the mast and rests upon the cross-piece 21.
- 15 The collar is split, as illustrated, and between the ears 48 at the ends of the collar is pivoted a cam clutch-lever 49, which is movable into and out of engagement with the mast, the shape of the cam and the location of its pivot
- 20 being such that the weight of the mast and the parts carried thereby will serve to rotate the cam into more intimate contact with the mast. The active position of the clutch-lever is maintained by means of a hook 50, which is slidably mounted upon the mast and is rotatable also thereon to engage and disengage the lever. The lever is curved as illustrated, so that it diverges downwardly from the mast, and by sliding the hook downwardly of the mast
- 25 and lever the lever is drawn toward the mast to press the cam more firmly against the mast. The split collar is provided with a laterally-directed lug or flange 52, which is perforated to receive a pin 53 in connection with a perforation 54 in the cross-piece 21 when it is desired to hold the mast against rotation. To hold the mast against upward movement when the hammer strikes the anvil or work thereon, a second collar 55 is
- 30 mounted on the shaft directly below the top of the arched frame. The upper collar is split, and between the ends thereof is pivoted the cam-shaped end of a second clutch-lever 56, the opposite end of which is swung downwardly
- 35 to engage the cam with the mast. The lever is held in active position by means of the hook 57, which is mounted slidably and rotatably on the mast, so that it may be swung into and out of engagement with the lever
- 40 and also adjusted to different points of the length of the lever to hold the latter with different pressures in active positions, it being noted that the lever is curved longitudinally. The upper split collar is held against
- 45 rotation by means of a pin 59, engaged with the flange 60 thereof and with the top of the arched frame. With this construction it will be seen that the mast may be held securely against vertical movement at any
- 50 point of its vertical adjustment and that by releasing the upper clutch-lever and withdrawing the pin from the lower split collar or clutch-ring the mast may be rotated to swing the hammer at different points of the
- 55 vertical adjustment of the mast.

It will of course be understood that it is desirable to hold the face of the hammer-head in different positions or at different angles to the face of the anvil under different working conditions, and for this purpose the head 61 of the hammer is pivoted to the handle 29 for movement in a vertical plane longitudinally of the handle. The handle adjacent to the head is screw-threaded, as shown at 62, and engaged with this threaded portion is a nut 63, which is grooved peripherally to receive a strap 64, to which are pivoted the ends of a bifurcated brace 65, which is pivoted also in the upper portion of the inner face of a hammer-head. By adjusting the nut on the handle the brace is shifted to swing the hammer-head pivotally, the nut serving also, in connection with the brace, to hold the head securely in its adjusted positions.

It will be understood that in practice modifications of the specific construction shown may be made, and any suitable materials and proportions may be used for the various parts without departing from the spirit of the invention.

What is claimed is—

1. An apparatus of the class described comprising a rotatable and vertically-adjustable mast, a pivoted hammer carried by the mast, separate means for holding the mast against vertical movement in opposite directions and means coöperating with one of said holding means for holding the mast against rotation.

2. An apparatus of the class described comprising a mast, a rocking seat carried by the mast, a hammer comprising a handle held in the seat and adjustable therein, a portion of the handle being threaded, a nut engaged with the threads of the handle, a hammer-head pivoted to the handle and connections between the head and nut for adjusting the head pivotally by movement of the nut.

3. An apparatus of the class described comprising a frame, a mast vertically and rotatably adjustable in the frame, a rock-shaft mounted at the upper end of the mast and provided with a seat, a hammer mounted in the seat and adjustable therein, said hammer comprising a handle, a pivoted head and means for pivotally adjusting the head upon the handle, means for rocking the shaft, adjustable means for holding the mast against vertical adjustment and means coöperating with one of said holding means for holding the mast against rotation.

4. An apparatus of the class described comprising a frame, a mast vertically and rotatably adjustable in the frame, adjustable clamps engaged with the mast and adapted to hold the latter against vertical adjustment, a rock-shaft carried by the mast, means for rocking the rock-shaft, means for holding the shaft normally and yieldably against the action of the rocking means, a seat carried by the rock-shaft, a hammer including a handle

mounted in the seat and provided with threads, a head pivoted to the handle, a nut adjustably engaged with the threads and connections between the nut and head for pivotally adjusting the latter, means for rotating the mast and means coöperating with one of the clamps for holding the mast against rotation.

In testimony whereof we affix our signatures in presence of two witnesses.

GEORGE E. WILLIAMS.
AURA M. WILLIAMS.
